(57) **CLAIM**

The ornamental design for a handle for portable electronic device case, as shown and described.

DESCRIPTION

FIG. 1 is a front perspective view of a handle for portable electronic device case showing our new design.

FIG. 2 is a rear perspective view thereof.

FIG. 3 is a front elevational view thereof.

FIG. 4 is a rear elevational view thereof.

FIG. 5 is a left elevational view thereof.

FIG. 6 is a right elevational view thereof.

FIG. 7 is a top plan view thereof; and,

FIG. 8 is a bottom plan view thereof.

The broken lines in the drawing figures form no part of the claimed design and depict portions of the handle for portable electronic device case that form no part of the claimed design.
